MOP

Melvin Severson, Galesville, Wis.

Application November 14, 1933, Serial No. 697,972

3 Claims. (Cl. 15—120)

This invention relates to improvements in the class of cleaning and pertains particularly to an improved mop structure.

The primary object of the present invention is to provide a novel and improved form of mop having a wringer mechanism associated therewith whereby the mop swab may be wrung out without having to be touched with the hands.

Another object of the invention is to provide an improved form of mop having means associated therewith for wringing the same, wherein the wringing mechanism will not interfere with the proper use of the mop.

A further object of the invention is to provide a mop having a wringing mechanism which is so designed that the swab portion of the mop remains free of connection with the wringing mechanism while it is in use and wherein the wringing mechanism when placed in operation will engage the mop swab at the outer end thereof and twist the same throughout its length.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in front elevation of the mop embodying the present invention;

Figure 2 is a view partly in side elevation and partly in vertical section of the same;

Figure 3 is a sectional view taken on the line 3—3 of Figure 1;

Figure 4 is a view in side elevation of the mop showing the wringing mechanism in position preparatory to wringing the mop element.

Referring now more particularly to the drawing wherein like numerals of reference indicate corresponding parts throughout the several views, the numeral 1 indicates the handle portion of the present improved mop structure, to the forward end of which is fixed the relatively broad head plate 2 at one side edge of which is formed the integral loop or eye 3, while adjacent the other end an aperture is formed to receive a bolt 4. Extending across one face of the head plate 2 is a clamping plate 5 which at one end has an aperture 6 in which the eye 3 of the head plate engages so that the clamping plate may be

readily swung relative to the head plate, as necessary when a mop swab is inserted or removed. Adjacent the other end of the clamping plate 5 from the end in which the aperture 6 is formed, there is formed a suitable aperture for the reception of the bolt 4, which bolt when in position in engagement with the two plates, has placed thereon the nut 7 which effects the drawing together of the two plates.

The mop swab is indicated as a whole by the numeral 8 and as shown this comprises a piece of material of suitable character and length which is formed in the shape of a loop, the ends of which are brought together between the plates 2 and 5 to be clamped therebetween.

The plates 2 and 5 are provided with the aligned centrally positioned apertures 9 and extending through these apertures is the short length 10 of a wringer shaft which is indicated as a whole by the numeral 11. This wringer shaft 11, is made up, in addition to the length 10, of a relatively long intermediate portion 12, the crank arm 13 and the handle portion 14 and these portions and the portion 10, are all pivotally joined together as indicated by the numerals 15, 15' and 15'' so that the portions 12, 13 and 14 may be arranged in alignment as illustrated in Figures 1 and 2, to lie against the handle 1 when the mop is to be used or, when the mop swab is to be wrung, the portion 12 may be swung out into alignment with the portion 10 so that it may be extended through the openings 9 so as to dispose the portion 10 in the forward end of the loop of the mop swab as illustrated in Figure 4. When in this position the crank portion 13 and handle portion 14 assume the positions illustrated so that the portion 12 may be turned about its longitudinal axis.

The free end of the portion 10 of the shaft has a pin 16 extending transversely therethrough which carries two rollers or sleeves each of which is indicated by the numeral 17 and between which the portion 10 is positioned. These rollers or sleeves may be made of any suitable material but it is preferred that they be made of rubber. These sleeves operate as stops to prevent the portion 10 of the shaft being drawn through the openings 9 when the wringer element is in inoperative position and when it is operatively connected with the mop swab 8 they are located in the forward end of the loop thereof as illustrated in Figure 4 so as to provide the necessary transverse elements to take a hold upon the mop swab and impart a twisting action thereto when the portion 12 of the shaft is rotated.

The handle 1 of the mop has mounted therein the two spaced spring fingers 18 between which the crank portion 13 of the shaft is frictionally held when the latter is disposed longitudinally of the handle in the manner illustrated in Figures 1 and 2.

From the foregoing it will be readily apparent that in a mop constructed in accordance with the present invention the swab thereof will be free for unrestricted movement during a mopping operation as the wringer element of the mop remains completely disconnected therefrom. When the mop swab is to be wrung out, however, the element 10 and parts carried thereby are readily shifted to operative position in the forward end of the swab loop so that when the intermediate portion of the shaft is rotated in the manner previously described the mop swab will be twisted up and thoroughly wrung out. The wringer element may then be reversely rotated and returned to its inoperative position without the necessity of the user of the mop touching the wet mop swab with the hands.

Having thus described the invention, what is claimed is:—

1. In a mop swab carrier designed to have a looped swab attached thereto, an elongated handle, a head plate carried by the handle and extending longitudinally from an end thereof, said plate having an aperture there, means for securing said swab to the plate, a shaft having one end disposed in the aperture in the plate and having an element extending transversely of the end for disposition within the swab, said shaft being divided into pivotally joined sections whereby the same may be shifted from a normal position longitudinally of the handle and said end portion thereof may be shifted through said aperture into the end of the swab loop remote from the plate and a crank formed to facilitate the turning of said end portion to effect the twisting of the swab.

2. In a mop swab carrier designed to have a looped swab attached thereto, an elongated handle, a head plate carried by and extending longitudinally from an end of the handle, said plate having an aperture extending transversely therethrough, a shaft made up of a plurality of hingedly connected sections, one of said sections being relatively short and normally extending through said plate aperture, a pin extending transversely of the said short portion of the shaft, a pair of roller members carried upon said pin with said shaft therebetween, and resilient means carried by the handle for securing the shaft to the handle, said shaft when released from said securing means being slidable through said head plate aperture and adapted to be broken to form a crank whereby to rotate the said short end portion of the shaft.

3. In a structure of the character described, an elongated handle, a relatively broad head plate secured to and extending from one end of said handle, a clamp plate disposed in opposition to one face of the head plate, a hinge connection between the clamp plate at one end and an adjacent end of the head plate, means for securing the clamp plate adjacent its other end to the head plate, said clamp plate being designed to secure a looped mop swab to the head plate, said plates having aligned apertures therethrough, a rod divided into a plurality of hingedly connected sections, one of said sections being relatively short and adapted to position in the aligned apertures with the other portion of the rod disposed against the handle, and a head formed across the end of the said short portion of the rod, said rod being extensible through said aligned apertures to position the last mentioned head in the forward end of a mop swab and adapted to have the pivotally connected portions thereof adjusted to form a crank for effecting the rotation of the said head.

MELVIN SEVERSON.
